UNITED STATES PATENT OFFICE.

CHARLES N. GALLOWAY, OF NEERSVILLE, VIRGINIA.

RURAL MAIL-BOX.

1,112,129.

Specification of Letters Patent.

Patented Sept. 29, 1914.

Application filed August 13, 1912. Serial No. 714,930.

To all whom it may concern:

Be it known that I, CHARLES N. GALLOWAY, a citizen of the United States, residing at Neersville, in the county of Loudon, State 5 of Virginia, have invented certain new and useful Improvements in Rural Mail-Boxes; and I do hereby declare the following to be a full, clear, and exact description of the invention, such as will enable others skilled 10 in the art to which it appertains to make and use the same.

This invention has reference to new and useful improvements in carrying devices and has particular reference to a rural mail box. 15 The purpose of the invention is to provide an efficiently operative structure embodying a box or carrier movable along a wire track way for transporting mail and parcels in rural districts, between a residence and road relatively distanced with respect thereto.

The invention further resides in the novel actuating mechanism by which the operation of the drive parts is arrested at each 25 end of the track way, and in which novel means is also provided for starting the drive parts of the device.

With the above and other objects in view, the invention consists of certain combinations and arrangements of parts as will be hereinafter more fully described and claimed, it being a still further object of the invention to provide a device which will not be likely to get out of working order.

Figure 1 is a side elevation of a self propelled mail box constructed in accordance with the invention and mounted upon a wire track way or aerial line supported upon suitable uprights or posts. Fig. 2 is an end elevation thereof, Fig. 3 is an enlarged vertical longitudinal sectional view of the mail box, more particularly illustrating the drive connections, Fig. 4 is a similar view but looking in the opposite direction from that shown in Fig. 3, Fig. 5 is a cross sectional view taken on the line 5—5 of Fig. 8, Fig. 6 is a longitudinal sectional view taken on the line 6—6 of Fig. 8, Fig. 7 is an enlarged detail view of the oppositely operable drive 50 mechanisms in a shifted position from that shown in Fig. 3, and Fig. 8 is a horizontal sectional view on the line 8—8 of Fig. 4.

In illustrating the practical embodiment of the invention, there is shown a pair of 55 end uprights or posts 10 and an intermediate upright or post 11, any number of which may be employed according to the distance

between the residence and the road. The intermediate post is provided with a bracket arm 12 upon which is supported an aerial line or wire 13, the extremities of which are connected to the posts or uprights 10 so that the latter members form abutments or stops for the car to be hereinafter described, when the same reaches its desired limit of travel.

The casing of the mail box is indicated by the numeral 14 and is provided at its ends with doors 15 for gaining access to the interior portion of the box which contains the mail. Each door is provided with suitable means for holding it in a locked position. It will also be observed that the box is substantially rectangular in cross section but has its upper portion or top wall 17 arched to provide a perfect drain surface and the box is divided horizontally by a partition 18 forming upper and lower compartments. A pair of hangers 19 extend upwardly from the top of the box near the ends thereof and rotatably support grooved wheels 20 which travel along the aerial line or wire and through the instrumentality of shafts 21 carry sprocket wheels 22 around which an endless drive chain 23 is engaged.

A frame standard 24 is pivotally mounted 85 on a shaft 26 which has its ends journaled in lugs 25 disposed on the intermediate portion of the partition 18, the standard being adapted for longitudinal movement with respect to the box. This standard rotatably 90 carries a transversely arranged shaft 27 on which a comparatively large sprocket wheel 28 is secured while an endless drive chain 29 is engaged around said sprocket 28 and a sprocket 30 mounted upon the extremity of 95 one of the shafts 21 for imparting rotation to the drive chain 23 to rotate the grooved wheels 20 and cause the box to move along the aerial line or wire. A governor is associated with the sprocket wheel 28 and embodies a substantially U-shaped bracket 31 carrying a vertical shaft 32 which has a pinion 33 at its upper end meshing with a pinion 34 carried by the shaft 27 while the lower end of the shaft 32 carries a pinion 100 35 meshing with a pinion carried by a flexible shaft 36 rotatably supported in a horizontal position and carrying on its outer portion, a governor including a wheel having weighted spring arms 37 and a hub having a brake disk 38 connected therewith to slide on the shaft according to the speed of rotation of the shaft 36 and the consequent bending of the arms. An upright 39 rota-

tably supports the outer end of the shaft 36 and has a bracket arm 40 pivotally supporting a brake member or lever 41 controlled by a rod 42 pivoted thereto, the governor serving to regulate the speed of rotation of the shaft 36 and consequently that of the drive chain and thereby controlling the velocity which the car will attain in moving along the aerial line or wire. The rod 42 is horizontally disposed and passed through one end of the casing, so that engagement of said rod with one of the end posts will apply the brake lever to the disk and bring the motor to a stop.

At each end of the upper compartment formed by the partition wall 18 is a spiral spring 43 each of which is inclosed in a barrel or case 44, each of the latter being provided with a gear 45 and each set of such parts being each rotatably journaled upon a shaft 46 transversely journaled within the casing. A gear 47 is disposed in mesh with each gear 45 and a removable turning crank 48 is provided to engage said gear by which the spring may be wound from the exterior of the box. Disposed in mesh with the gear 45 is a gear 49 with which is associated an escapement wheel 50 having a pallet 51 cooperating therewith and pivotally supported upon the support for the gear as shown at 52. The standard 24 also carries a cross arm 53 arranged to engage the pallets or pawls 51 upon opposite movement of the standard 26 to cause the pinion or gear 54 fixedly mounted on the shaft 27 adjacent to the standard, to be moved into engagement with either of the gear wheels 49 to cause the reverse rotation of the shaft 27 and consequent opposite movement of the carrier or box along the track way. The brake lever 41 has an oppositely extending rod 55 connected therewith, the same being movably supported on the arm 40 and operating through the opposite end of the casing so that as the box strikes one of the end poles said rod will be thrown in an opposite direction to cause movement of the brake lever and consequent application of the brake, while opposite gearing of the parts to move the car in the opposite direction will result when the governor is released. The governor has of course been previously brought stationary upon the arrival of the box at the end of the wire or aerial line owing to the fact that the brake lever will strike the friction disk and bring the motor to a stop and it will thus be evident that continued operation of the device may be accomplished by moving the brake or clutch out of operation and the car thereby directed toward the road way or the residence as the occasion may require.

From the foregoing description taken in connection with the accompanying drawings, it will be evident that I have provided a mail box and carrier device which will greatly assist in the convenience in transporting mail to and from the road in rural districts where it usually is necessary to leave to mail at the road some distance from the residence and by this means, loss of mail and the inconvenience of traveling back and forth between the road and residence will be obviated.

Having thus described my invention what I claim is:

1. A mail box delivery apparatus embodying a track wire, a receptacle, hangers carried by the receptacle adjacent each end thereof, shafts rotatably carried by the hangers, grooved rollers mounted on the shafts and engageable along the wire, drive sprockets carried by the shafts, chains connecting said sprockets, means for rotating the said shafts simultaneously and including a pivoted standard, a pinion rotatably carried by the standard, spring motors alternately intergearable with the pinion, means operated by the movement of the standard to cause one motor to be brought stationary and the other for operation at each end of the wire and means for controlling and arresting the speed of rotation of the pinion and its intergeared connection with the first named shafts.

2. A delivery apparatus comprising a track wire, a receptacle, wheels carried by the receptacle and engaging said wire, drive means carried by the receptacle, intergeared connections between the drive means and the wheels for driving the receptacle, a governor for regulating the speed of the intergeared connections and means connected to said governor and extending exteriorly of the receptacle whereby pressure against said means will actuate the governor to stop the driving means.

3. The combination in a delivery apparatus including a traveling member, a driving mechanism therefor and a governor for regulating the drive mechanism and including a friction plate, of a lever pivoted intermediate of its end, a brake shoe at one end of said lever engageable with the friction plate, and slidably mounted rods connected to the lever on opposite sides of its pivot and extending outwardly of the ends of the traveling member.

In testimony whereof, I affix my signature, in presence of two witnesses.

CHARLES N. GALLOWAY.
